UNITED STATES PATENT OFFICE.

WILLIAM CAMERON, OF SUEZ, EGYPT, ASSIGNOR TO SIMPLEX REFINING COMPANY, OF SAN FRANCISCO, CALIFORNIA, A CORPORATION OF CALIFORNIA.

PROCESS FOR DEHYDRATING EMULSIONS.

Application filed November 15, 1920. Serial No. 424,112.

To all whom it may concern:

Be it known that I, WILLIAM CAMERON, a subject of the King of Great Britain, residing at Suez, Egypt, have invented a new and useful Process for Dehydrating Emulsions, of which the following is a specification.

My invention relates to the art of removing water from emulsions or distilling crude oil or distillate but is particularly applicable to petroleum emulsions containing water having a considerable salt content. Such oils occur in many parts of the world and are commonly referred to as "salty crudes." It is a well known fact that water may be removed from such oils by heating, but great difficulty is found in operating the ordinary type of heating apparatus due to the tendency of the salt or other water soluble matter to deposit on the heating surfaces. While of course sodium-chloride is the commonest of these water soluble substances, there are various magnesia, lime and other salts which are found in such water. All of these salts behave in a similar manner, depositing on the heated surfaces where they form a thick shell or scale. This scale is a poor conductor of heat and wherever it forms there is a tendency for the surface to overheat, blister and become destroyed.

In the ordinary operation of stills on these salty crudes a very rapid clogging up of the still and deterioration of its heat surface is noted. I have discovered that this deposit of solid matter is due to a local evaporation from the heating surfaces which may occur even where the oil is very much below the boiling point of water. This, I believe, is due to the fact that the water particles tend to adhere to the surfaces of the metal and to absorb heat therefrom becoming heated above the boiling point although surrounded by oil which may be very much below the boiling point. As a result these small globules or particles of water are converted into steam leaving any dissolved matter in the form of a solid adhering to the metal surface. The steam so produced is probably almost immediately recondensed forming a drop or drops of water which are without any appreciable saline content.

I have found that where a body of oil is allowed to stand in contact with the heating surface that a very large deposit of saline matter may occur on the heating surface

although the oil is far below the boiling temperature of water. My invention overcomes this difficulty by evaporating the water without allowing it to come in contact with heated surfaces of any kind.

Further objects and advantages will be made evident hereinafter.

In the drawing which is for illustrative purposes only,

Fig. 1 is a diagram of the apparatus employed and Fig. 2 is a flow diagram of the process.

The apparatus employed consists of a make-up pump 11, a circulating pump 12, a vaporizing chamber 13 and a heater 14. The oil to be dehydrated is delivered by the pump 11 through a pipe 20 into a pipe 21 leading to the top of the vaporizing chamber 13. In this vaporizing chamber the oil falls on a spreader 22 which covers the end of the vapor outlet pipe 23, the end of which is perforated with several openings as shown at 24. The oil falls into the bottom of the vaporizing chamber as shown at 25. This oil is constantly circulated by means of the pump 12 through pipes 26 and 27 into the heater 14 where the oil is heated above the boiling point of water. This oil is delivered through a pipe 28 into the pipe 21.

The apparatus is preferably charged originally with oil containing no water, this oil being circulated to and from the fuel supply 25 of the vaporizing chamber 13 until the whole mass of this oil is somewhat above the boiling point of the water. The salty crude is then admitted through the pipe 20, the circulation being, however, maintained. This salty crude mixes with the highly heated oil in the pipe 21, the mixture being released above the spreader cone 22, falling downwardly through the vaporizing chamber 13. The greater portion of the water and distillate is vaporized and passes away to a condenser by the pipe 23. Any water, however, which falls into the bulk supply 25 being converted into steam. All of this steam together with the lighter portions of the oil are also carried off in the form of vapor through the pipe 23, leaving the oil and the saline matter in the bottom of the vaporizing chamber 13.

I have discovered that the salts in their solid form when freed from water will float in suspension in the body of oil without any tendency to adhere to metal surfaces. I am

therefore able to constantly withdraw a portion of the oil through a pipe 30 controlled by valve 31, this dehydrated oil containing the solids in suspension but being free from water. This oil may be handled in ordinary stills if desired without danger of the formation of scale due to the saline matter contained therein.

What I claim is:—

- 10 1. A process of treating emulsions containing water having water soluble salts in solution therein comprising injecting said emulsion into a body of oil having a temperature above the boiling point of water, allowing the water vapor so produced to escape freely and maintaining the temperature of said oil by circulating dehydrated portions thereof over heated metal surfaces.
- 15 2. A process of treating emulsions containing water having water soluble salts in solution therein comprising injecting said emulsion into a body of oil having a temperature above the boiling point of water, allowing the water vapor so produced to escape freely, and maintaining the temperature of said oil by circulating dehydrated portions thereof through heated chambers.
- 20 3. A process of treating emulsions containing water having water soluble salts in solution therein which comprises circulating a closed ring of dehydrated oil from and to a bulk supply thereof, maintaining the temperature of said oil above the boiling point
- 25
- 30

of water by the application of heat to said ring, injecting the emulsion to be treated into said dehydrated oil and allowing the vapors so produced to escape freely.

4. A process of treating an emulsion having water soluble salts in solution therein which comprises: circulating dehydrated oil around a closed ring containing a heater and a vaporizing chamber; injecting the emulsion into said ring after the dehydrated oil leaves the heater; and withdrawing the water vapor from said vaporizing chamber, the oil leaving the heater being at a temperature in excess of the boiling point of water at the pressure found in said vaporizing chamber.

5. A process of treating an emulsion having water soluble salts in solution therein which comprises: circulating dehydrated oil around a closed ring containing a heater and a vaporizing chamber; injecting the emulsion into said ring after the dehydrated oil leaves the heater and before it reaches the vaporizing chamber; and withdrawing the water vapor from said vaporizing chamber, the oil leaving the heater being at a temperature in excess of the boiling point of water at the pressure found in said vaporizing chamber.

In testimony that I claim the foregoing as my invention I have signed my name this 11th day of October, 1920.

W. CAMERON.
